UNITED STATES PATENT OFFICE.

HENRY W. McCOMBS, OF BOSTON, MASSACHUSETTS.

STEAM-CYLINDER DRAIN-VALVE.

SPECIFICATION forming part of Letters Patent No. 667,244, dated February 5, 1901.

Application filed August 8, 1900. Serial No. 26,285. (No model.)

To all whom it may concern:

Be it known that I, HENRY W. McCOMBS, a citizen of the United States of America, and a resident of Boston, in the county of Suffolk and State of Massachusetts, have invented 5 certain new and useful Improvements in Steam-Cylinder Drain-Valves, of which the following is a specification.

My invention has for its purpose the liberation of condensation from the steam-cylinders of stationary and marine engines, while it is particularly applicable to the cylinders of locomotives.

My present invention is an improvement 15 over my former patents numbered 651,878 and 651,879, dated June 19, 1900, whereby I am enabled to dispense with the cylinder-cocks and their appurtenances shown in the former and the cylinder-cocks, cylinder-cock slides, and right and left piston-rods shown in the latter.

It further consists in simplifying the construction of the supply-cock, reducing the number of its ports and ducts, insuring its 25 efficiency in a frigid temperature, and in other essential features of improvement, which will be hereinafter described, and particularly defined in the claims.

Referring to the drawings forming part of 30 this specification, Figure 1 exhibits fragmentary elevations of the forward and rearward parts of a locomotive with my assembled invention thereto attached. Fig. 2 is an elevation of the supply-cock in normal or running 35 position, Fig. 3 being a vertical longitudinal section on line 3 3 of Fig. 6 in open position, with the accessories of the operating-lever also in vertical section. Fig. 4 represents a plan similarly positioned as to its parts. Fig. 5 designates a plan of the bottom of the 40 same. Fig. 6 is a transverse section of the supply-cock and its coacting valve to disclose its ports, ducts, and steam-cavity on line 6 6 of Fig. 3. Fig. 7 exhibits an enlarged vertical section of the lever and parts actuating the supply-cock valve; Fig. 8, a plan and a transverse section of the graduating-plate. Fig. 9 is a horizontal longitudinal section of 45 the drain-valve case, exhibiting the duplicate steam-ducts and steam-heating vents. Fig. 50 10 exhibits a plan of the piston, showing its

packing-rings. Fig. 11 illustrates a portion of a steam-cylinder with my improved drain-valves suspended at each end thereof, shown in longitudinal section and in side elevation 55 in open position, and Fig. 12 is a perspective of one of said drain-valves detached from the steam-cylinder.

Similar letters of reference indicate like parts throughout the several views, referring 60 to which—

A denotes the cab of the locomotive, within which, accessible to the engineer, is attached to the head of the boiler the supply-cock B. Leading therefrom are the pipes C and D, 65 conveying steam or air under pressure to and from the drain-valves F F, secured to the under sides of each of the steam-cylinders to liberate the water of condensation therefrom and also in a frigid atmosphere to additionally convey a moiety of live steam to the drain-valves, raising the temperature therein to insure the proper operative condition of the valve parts. The exhaust-pipe of said supply-cock is seen at E. This is a summary 75 of the operation of my improved invention.

In its present construction my supply-cock comprises the casing M, containing the steam-chamber H, Fig. 3, and the semirotative or oscillating valve-disk I' therein, having a vertical port I, a steam-cavity I², and two heating-vents I³ I⁸, with a projection I⁴ on its upper face, by which it may be semirotated by devices presently described. A lower body J, Fig. 5, has three vertical ducts J' J² J³, communicating or non-communicating with said port I and steam-cavity I², as the exigencies of the operations may require. Said ducts J' J² connect with the conducting-pipes C D, respectively, leading to the drain-valves, 80 while the duct J³ communicates with the exhaust E and the heating-vents I³ I⁸ (when employed) with the ducts J' J², the handpiece R resting at "heater" position, Fig. 8, said body J being united to the casing M by the 85 series of tap-bolts O. To actuate the valve I', previously described, its projection I⁴ is embraced by the bifurcated stem P, carrying a steadyng-plate N, and above it a protective gasket N'. The said stem has a suitable packing, as at Q, while the upper end is squared, so as to attach to the hand-lever R, through 90 95 100

which the stem P of the supply-cock valve I' is manipulated to perform its functions in connection with the steam or air ducts in the body J, hereinafter specifically set forth in 5 the description of the operation. To accurately gage the several positions of said lever R, and concurrently the valve I', the gage-plate S, Fig. 8, secured to the top of the casting M, or it may be integral therewith, is provided with end stops S², limiting the action 10 of the lever R, and four concave ball-rests S', which underlie the path of the lever R as it is swung from one position to another, which positions may, if desired, be indicated upon 15 the plate. The devices coacting with said depressions S' are contained in the cylindrical taper-bottomed chamber T, forming an integral part of the lever R. Said chamber incloses the arresting-ball U, which is forced 20 into one of the depressions S' during the intervals of semirotation by the spring-actuated plunger V. Its stem V', enveloped by the spring W, recoils under sliding pressure (as when resting upon the plate S) within the 25 recess X of the binding-screw Y, confining the described parts within the chamber T. The aggrouped devices are supported by the threaded stem and bracket, as at Z, Fig. 3, and confined by a check-nut in the ordinary 30 manner.

I proceed with a description of my improved drain-valve, (exhibited in Fig. 11,) comprising the valve-case F, provided at one end with the screw-cap F⁵ and its opposite end with a 35 similar threaded cap F⁶, with a stuffing-box thereto connected, through which passes the hand-rod F⁷, secured to the piston K to actuate the same irrespective of the medium described. To reciprocate said piston with 40 steam or air, two ducts F⁸ F⁴, Fig. 9, lead to the ends F' F² of the piston-chamber, whence the actuating medium from the reservoir through the pipes communicating with said ducts F⁸ F⁴ impinge upon one end of the piston K or the other, impelling it to the position observed in Fig. 11, closing simultaneously the passage L and the drain-vent L', as described, each forming an integral part of the case F.

50 Details of the operation are as follows: Commencing with the supply-cock B, Fig. 3, which is shown in open operating position, steam or air under compression is admitted from a reservoir (not illustrated) conveniently 55 situated on the locomotive, passing through the pipe G to the chamber H, filling the same and entering the vertical port I in the semi-rotative valve I', thence passing through the communicating duct J' in the lower body J of 60 the supply-cock B, entering the pipe C, leading to the duct F³ in the chamber end F' of the drain-valve F, thrusting the piston K, reciprocating in said valve-chamber, to the position illustrated. Thus its circumferential de- 65 pression K² simultaneously opens the steam- passage L, communicating from the steam-cylinder to the drain-valve chamber, and the

drain-vent L', which carries off the surface condensation. Should there exist any residue of steam or air in the opposite chamber 70 end F² of the drain-valve F, it is forced upward through duct F⁴ and pipe D to the supply-cock B, through duct J² into the steam-cavity I², (also in the semirotative valve I',) thence to the vertical duct J³, Fig. 6, and exhausted 75 outwardly, as before, at E. Should the hand-lever R be now moved to the closed position, (see Fig. 8,) the valve I' is thereby semirotated, bringing its port I in alinement with duct J², (see Fig. 6,) permitting the steam or 80 air to pass from the reservoir through pipe D to duct F⁴ in the camber end F² of the drain-valve F, forcing the piston K to the piston-chamber end F', thus simultaneously closing the steam-cylinder passage L and also the 85 drain-vent L' by the circumferential shoulder K'. The surplus of steam, if existing in the chamber end F', is then returned through duct F³ to pipe C, through duct J', Fig. 6, steam-cavity I², and duct J³, the three latter being now in alinement, whence it passes 90 through the exhaust E and to the atmosphere, as before.

The arrangements for heating the drain-valves, so as to insure their working condition in a freezing temperature, are as follows: Swinging the lever R to the position marked "Heater," Fig. 8, brings each of the vertical heating-vents I³ I³, Fig. 6, situated in the valve I' and contiguous to its port I and steam-cavity I², in alinement with the ducts J' and 100 J², admitting small jets of live steam through the conducting-pipes C and D, entering the piston-chamber ends F' F² through the inclined ducts F⁸ F⁴, Fig. 9, and escaping through 105 the drip-vents F⁸ F⁸, Fig. 9.

The merit of my present invention consists in its economy, simplicity, and adaptability to the results sought to be attained without detracting from the working efficiency of my 110 previous patents hereinbefore alluded to.

Having ascertained these improvements through the preferred details of construction illustrated, they are subject to modifications which would not depart from the spirit of my 115 invention and are intended to be included in the claims.

I claim—

1. An improved steam-cylinder drain-valve for exhausting the surface condensation from 120 steam remaining in said cylinders, the right and left inclined ducts provided in the wall thereof to admit and eject air or steam, means for conducting the actuating medium from the engine, the piston-chamber adapted to receive said medium, the vertical central inlet- 125 passage connecting with the steam-cylinder, the drain-vent immediately beneath the inlet- passage and means reciprocating within said piston-chamber to control the inlet and outlet passages.

2. In an improved apparatus for draining the cylinders of engines of surface condensation, the supply-cock having a circular cham-

ber, the valve semirotating therein provided with one vertical port and one steam-cavity, in combination therewith the lower fixed body J, having two vertical ducts communicating with the conductors of the actuating medium from the engine to its steam-cylinders, and one vertical duct communicating with the exhaust, said vertical port and steam-cavity adapted to open or close said vertical ducts, and means to actuate said valve for the purpose herein disclosed.

3. In an improved drain-valve the supply-cock having an internal steam-chamber and ducts leading therefrom, the semirotative valve therein having a vertical port and a steam-cavity arranged to intercommunicate at predetermined intervals with said ducts, the drain-valves having each a chamber with inlet and outlet passages, the pistons reciprocating within said chambers and means to conduct the actuating medium from the engine thereto, in combination therewith the tapered cylindrical chamber, the spring-impelled plunger therein, the arresting-ball cooperating with said plunger, and with the gage-plate, the said plate, and the binding-screw provided with a recess to receive the recoil of the plunger-stem.

4. In a supply-cock having a steam-chamber and a lower body J, with inlet and outlet ducts, the valve-disk provided with a port and a steam-cavity, the heating-vents I³ contiguous to the vertical ducts in said lower body, arranged and adapted to coact with the supply-cock ducts J' J² to transmit continuously a moiety of live steam so long as the operating-lever is thrown to the position indicated as "Heater," thus preventing con-

gelation within said ducts in a freezing temperature.

5. In combination the supply-cock having an internal lower body provided with three vertical ducts, a semirotative valve, means to actuate said valve, an intervening chamber to contain and means to receive the actuating medium from the engine; the hand-lever R, provided with an extension adapted to secure the supply-cock-valve stem, the circular chamber within said lever, having a converging bottom, the arresting-ball coacting with said taper, the spring-impelled plunger actuating said ball, means to receive the ball at its lowest position to arrest and confine said hand-lever and through it the supply-cock valve in prearranged positions, and the binding-screw provided with a recess to engage with the plunger-stem.

6. The combination of the organized mechanism for actuating and accurately gaging the semirotations of the supply-cock valve comprising the lever R and its contained devices previously described, with the drain-valve having inclined ducts and outlets leading to and from the chamber thereof, the said chamber, the piston reciprocating in the chamber adapted to control said inlets and outlets, the circumferential depression therein, the abutting shoulder and means to actuate said piston independently of the actuating medium.

Signed by me at Boston, Massachusetts, this 2d day of August, 1900.
